UNITED STATES PATENT OFFICE.

ANTHIME BERNIER, OF MONTREAL, QUEBEC, CANADA.

METAL TIE AND RAIL CHAIR.

Application filed September 9, 1922. Serial No. 537,084.

To all whom it may concern:

Be it known that I, ANTHIME BERNIER, a subject of the King of Great Britain, and residing at the city of Montreal, in the Province of Quebec, in the Dominion of Canada, have invented a new and useful Metal Tie and Rail Chair, of which the following is the specification.

The invention relates to metal tie and rail chair as described in the present specification and illustrated in the accompanying drawings that form part of the same.

The invention consists essentially of the novel features of construction pointed out broadly and specifically in the claims for novelty following a description in detail of the preferred form of the invention.

The objects of the invention are to furnish a tie that will replace the wooden rail-way tie and eventually eliminate the use of wood for that purpose; to lighten the weight of the casting without diminishing the strength; to facilitate the laying of the rails; to insure reliable and tight joints; and generally to provide a permanent tie that will reduce the cost of maintenance and increase safety to the public in railway travel.

In the drawings, Figure 1 is a plan view of the tie showing the rails broken away.

Figure 2 is a longitudinal sectional view of the tie showing the rails in cross section.

Figure 3 is a cross sectional view on the line A—A in Figure 1.

Figure 4 is a cross sectional view on the line B—B in Figure 1.

Figure 5 is a detail of a bolt suitable for use with this invention.

Figure 6 is a cross sectional view on the line C—C in Figure 1.

Figure 7 is a detail of a fastening plate.

Like numerals of reference indicate corresponding parts in the various figures.

Referring to the drawings, the body 1 of the tie is formed of a casting or rolled plate 45 preferably of iron having the rail chair ends 2 and 3 converging at each inner end to the narrow neck 4 and the longitudinal slots 5 and 6 in each of the said chair ends 2 and 3 providing a central bar 7 forming a continuation of the neck 4.

The triple lugs 8 and the triple lugs 9 project outwardly from the chair ends 2 and 3 respectively, the central lugs projecting from the central bars 7 towards the inner 55 ends and the outer lugs projecting from the outer bars 10.

The central lugs are reinforced by the rib 11 extending along the neck 4 into said lugs and the outer lugs are reinforced by the short ribs 12.

The single lugs 13 and 14 are the full width of the chair ends 2 and 3 and form the recesses 15 and 16 for the joint plate and rail base respectively with vertical inner walls 17 and 18 corresponding to similar vertical walls in the recesses 19 and 20 formed by the triple lugs 8 and 9.

The single lug 14 is closer to the triple lugs 9 than the single lug 13 is to the triple lugs 8 as where the chair ends support the rail 21 intermediate of its length only a fastening plate 22 is necessary, but where the rails 23 and 24 meet on the chair 2 the joint plates 25 and 26 are required.

The plate 22 is formed with the base 27 wedge-shaped to fit in the recess 20 and the extension 28 covering the rail base and merging into the vertical flange 29 against the web of the rail. The upper face of the extension 28 is flattened for bolt heads and so the bolt holes 30 with key slots 31 extend through the plate.

The joint plates 25 and 26 are similarly formed and the same indicating numerals apply but the plates fit into the recesses 15 and 19.

The bolts 32 are made with the square or polygonal head 33 and plain stem 34 having the keys 35 from the stem under the head and the keys 36 at right angles to the keys 35 from the stem at the lower ends.

The key bolts 32 in completing the fastening, are inserted through the joint plates, rail bases and tie, the slots 37 for the lower keys 36 extending through the metal of the tie into the circular recesses 38 in which the keys 36 may turn freely. The key bolts 32 are turned in the recesses 38 before the upper keys 35 are inserted in the key slots 31, therefore the keys 36 are out of register with the slots 37, when the upper keys are in place in the slots 31.

In installing these ties and chairs the rails are laid between the outer single lugs and inner triple lugs and where a joint of two rails occurs joint plates are inserted and driven in until they register with the holes in the rails and in the ties when the bolts are dropped in and turned until the top keys find the key slots in the plates. Only the single fastening plate is needed where the rail passes over a tie and this is driven in

and locked by bolts in the same way as the joint plates.

What I claim is:

1. In a metal tie and rail chair, a body having rail chairs at the ends and bolt holes through said chairs, fastening plates having bolt holes therethrough and extending over the rail base, and bolts in said holes and adapted to be inserted through the rail base and lock under said body.

2. In a metal tie and rail chair, a body having a reinforced neck portion connecting two broadened ends slotted longitudinally forming central and outer bars, the

latter having slotted bolt holes leading to recesses in the under faces, each broadened end having triple inner lugs and single outer lugs, fastening plates engaging in recesses formed by said lugs and having key slotted bolt holes, rails having bolt holes, and bolts having a suitable head and upper keys under said head engaging the plates in said key slots and lower keys at the end of the stem engaging said outer bars beyond the key slots.

Signed at Montreal, Canada, this 14th day of August, 1922.

ANTHIME BERNIER.
